UNITED STATES PATENT OFFICE.

JOEL BLOMSTER AND JOSEPH SCHABEN, OF ALGONA, IOWA.

AUXILIARY ATTACHMENT FOR ENGINES.

1,279,973.

Specification of Letters Patent. Patented Sept. 24, 1918.

Application filed December 23, 1916. Serial No. 138,660.

To all whom it may concern:

Be it known that we, JOEL BLOMSTER and JOSEPH SCHABEN, citizens of the United States, residing at Algona, in the county of Kossuth and State of Iowa, have invented certain new and useful Improvements in Auxiliary Attachments for Engines; and we do hereby declare the following to be a full, clear, and exact description of the invention, such as will enable others skilled in the art to which it appertains to make and use the same.

This invention relates to motor vehicles, and more particularly to an auxiliary attachment for the engine thereof.

The principal object of the invention is to provide means whereby superheated steam may be conveyed into the intake manifold of the engine and mixed with the hydrocarbon gas in its passage into the engine, so as to reduce the consumption of gas, this mixture of gas and superheated steam serving effectively to prevent the engine from carbonizing and at the same time increase the power and efficiency of it.

A further object of the invention is to take steam from within the top of the radiator of the motor vehicle, subsequently superheat it and then deliver it to the intake manifold for mixture with the hydrocarbon gas.

A still further object of the invention is to position a steam dome upon the exhaust manifold of the engine into which steam is conveyed from the radiator, where it is superheated and subsequently conveyed to the intake manifold.

With these and other objects in view as will appear as the description proceeds, the invention comprises the various novel features of construction, combination and arrangement of parts as will be more fully described hereinafter, and set forth with particularity in the appended claims.

Referring to the drawings,

Figure 1 is a perspective view of our improved device shown attached in operative position upon a motor vehicle engine.

Fig. 2 is a vertical transverse sectional view taken on the line 2-2 of Fig. 1.

Fig. 3 is a fragmentary longitudinal sectional view through the steam dome and a portion of the exhaust manifold to which it is attached.

Similar characters of reference are used to denote like parts throughout the accom-

panying drawings and the following description.

Referring more particularly to the drawings, the reference numeral 1 indicates a steam dome that is designed to be suitably attached upon the exhaust manifold 2, which in this instance is securely attached thereto. While the dome 1 in this instance is shown to be of substantially cylindrical shape as indicated by the numeral 3 and which is provided with a dome shaped top 4, it is to be understood that it can be made of any desired shape or design found best suited for the purpose intended.

Tapped into the upper portion of the steam dome 1 is one end of a steam conveyer pipe 5, the opposite end of which is attached to a nipple 6 carried by the radiator 7, through the medium of a union nut 8. From this nipple 6 an auxiliary steam conveyer pipe 9 extends in and transversely across the upper portion of the radiator and terminates in a vertically disposed stand-pipe 10, which extends upwardly within the radiator filler tube 11 to a point adjacent the filler cap 12.

Tapped into the opposite side of the steam dome 1 is one end of a steam conveyer pipe 13 which extends downwardly and has its opposite end attached to a union or T coupling 14. A nipple or short conveyer pipe 15 has one end attached to this T coupling 14 and the other end tapped into the intake manifold 16. Another conveyer pipe 16 has one end attached to the coupling 14 and its opposite end tapped into the intake manifold neck 17 at a point below the connection of the pipe 15 with the manifold 16.

From this construction just described it will be apparent that the steam will be taken from the top of the radiator and conveyed through the auxiliary conveyer pipe 9, and the pipe 8 into the steam dome 1, where it will be superheated from the heat radiated from the exhaust manifold 2, and subsequently conveyed through the pipe 13 through the intake manifold where it is intermixed with the hydrocarbon gas 10 in its passage into the engine.

It is to be noted that steam only is conveyed from the radiator to the superheating steam dome after the motor has been in operation for some time, and since the conveyer pipes enter and leave the steam dome from the upper portion thereof it will be

apparent that in the initial starting of the engine, the moist air which will be drawn from the radiator into the steam dome will be more or less condensed so that practically all moisture contained within the air will be condensed and accumulated within the steam dome upon the exhaust manifold. As soon as the exhaust manifold begins to become heated, the condensation or moist air or vapor within the steam dome will be vaporized and converted into steam for its passage into the intake manifold. After the engine has become thoroughly heated, the heat radiated from the exhaust manifold will operate to effectively superheat all steam that is conveyed into the steam dome from the radiator.

It will also be noted that by reason of the particular position of the auxiliary conveyer pipe 9, that the hot water in its circulation through the water cooling system of the motor will freely circulate around this pipe so as to provide additional means for heating it, whereby the steam in its passage from the radiator through the steam dome will be initially heated prior to its being superheated within the steam dome.

If it should be found desirable a controlling valve may be positioned between the steam dome 1 and the intake manifold so as to control the passage of the superheated steam into the manifold.

What we claim is:

1. In a motor vehicle, the combination

with the engine thereof and its associated parts, of a cup shaped steam dome mounted upon and secured to the exhaust manifold, a conveyer pipe entering said steam dome adjacent its upper end and establishing communication between the steam dome and the radiator, and a conveyer pipe entering said steam dome adjacent its upper end and establishing communication between said steam dome and the intake manifold of the engine, said steam dome adapted to arrest condensed steam and prevent it from entering into the intake manifold.

2. In combination with an internal combustion engine and its radiator, of a moisture superheater comprising a hollow element positioned to lie adjacent the engine exhaust pipe, a pipe connection between said element and said radiator above the radiator water level, and a pipe connection between said element and the engine intake manifold, both pipe connections into said element being above its bottom wall to thereby form a condensation space between said connections and the bottom wall of said element.

In testimony whereof we have signed our names to this specification in the presence of two subscribing witnesses.

JOEL BLOMSTER.

JOSEPH SCHABEN.
